UNITED STATES PATENT OFFICE.

JOHN OSCAR EMRICH, OF ALLEGHENY, PENNSYLVANIA.

FIREPROOF DOOR:

No. 876,787.

Specification of Letters Patent.

Patented Jan. 14, 1908.

Application filed April 22, 1907. Serial No. 369,523.

To all whom it may concern:

Be it known that I, JOHN OSCAR EMRICH, a citizen of the United States, resident of Allegheny, in the county of Allegheny and State of Pennsylvania, have invented a new and useful Improvement in Fireproof Doors; and I do hereby declare the following to be a full, clear, and exact description thereof.

My invention relates to the construction of a fireproof door, and has for its object the construction of such a door of sheet steel, wire glass, and other fire retarding materials arranged, combined, and secured together in a novel manner, for the purpose of forming a most formidable fire-door.

A further object of my invention is to effect such a construction of fire-door at an economical cost on account of the simplicity of the manner of forming the steel parts and of combining the same.

Referring to the drawings, Figure 1 is a view in elevation of a door embodying my improved construction. Fig. 2 is a horizontal section on lines 2—2 of Fig. 1. Fig. 3 is a broken elevation on an enlarged scale, showing the interior arrangement. Fig. 4 is a horizontal section on lines 4—4 of Fig. 3. Fig. 5 is a section on lines 5—5 of Fig. 3. Fig. 6 is a plan or top view on lines 6—6 of Fig. 1 of especially devised lock bolster. Fig. 7 is a view in perspective, showing the construction of the rails of the door at the point of abutment or connection with the stiles. Fig. 8 is a perspective of the end of the stile showing its construction and adaptability for engagement with the rail. Fig. 9 is a view in perspective of a clamp adapted to bind together the rails and stiles. Fig. 10 shows in perspective a pin fitted with keys and set-screws.

Like references in the specification refer to like parts in the drawings, in which A represents a door frame formed of the stiles *a* and rails *a'* made of sheet steel, and each having a marginal angular formation *a²* lengthwise thereof, the adjoining parts of said stiles and rails being turned inwardly to form the obtuse angles *b* (Figs. 7 and 8) which are adapted to be engaged by the clamp *b'* (Fig. 9) being inserted through the opening *b²* in the rail *a'* and open ends *c*, the angles *b* and clamps *b'* being thoroughly clamped together (Figs. 3 and 4) to form the frame, after which the part *d'* is forced down closing the corner *b²* of the rail *a'* after which the

part *d* is forced over to close the open end of the stile *a*, these parts being held in position by machine screws *d²* engaging the nut *e* which is secured to the underside of the part *d'*, as shown in Fig. 3, the marginal angle *a²* forming a panel around the plane between the stiles and rails.

Within the space between the walls of the frame A are sheet-steel plates or panels *e'*, one being secured to each side thereof preferably covering a little more than the plane between the stiles of the frame, except at the point opposite the hinges *e²* where said plates are extended forming arms *f* which are flanged and folded and bear against the narrow or hinge bearing stile of the door, as at *f'*, making a strong bearing or support for the hinges *e²* and also at a point in the opposite stile where the panels *e'* are also extended to form the support or bolster *g* (Fig. 6) which forms a particularly advantageous means for carrying the lock of the door.

Behind each steel panel or plate *e'* is a sheet of asbestos *g'* each of which is backed by a sheet of wire glass *h* which have an intervening air space *i* between them, the air space being maintained by asbestos pads *h'*. At several points preferably in and around the marginal angle *a²*, perforations (not shown) are made, which extend through the interiorly arranged sheet-steel panels *e'*, asbestos sheets *g'* and wire glass *h*, through which perforations the pins *j* are inserted so that the ends thereof extend sufficiently on each side of the frame to allow the tapered keys *j'* to be inserted in the key-ways *j²* where they are held in fixed position by the set-screws *l*. (Figs. 3 and 10.) Fitting neatly over and around the marginal angle *a²* on each side of the frame A and covering the ends of the pins *j'* is a molding *k* which is held securely in position by the machine screws *d²* engaging the tapped holes *m* of the pins *j*, the heads of all machine screws being afterwards ground down flush with the face of the molding *k*. The molding is then arranged in position and secured to the ends of the pins *j* by machine screws engaging the tapped hole to complete the door.

Various changes may be made in the construction herein shown and described, such as the interposing of center stiles and rails, and the forming of several panels instead of one, and the re-inforcing of the upper rail instead of the hinge bearing stile for the pur-

pose of a sliding door so that I do not desire to limit myself to the particular style of door herein shown.

What I claim as my invention and desire 5 to secure by Letters Patent is:—

1. In a fire-door having suitable hollow stiles and rails adapted to be clamped together, clamps adapted to engage said stiles and rails, sheets of fire retarding material 10 having an intervening air space arranged within the stiles, rails and panels; pins extending through the door, and means on the ends of the pins for supporting the sides of the stiles and rails and the interiorly arranged parts 15 compactly together.
2. In a fire-door having hollow stiles and rails, a clamp adapted to engage said stiles and rails, sheets of fire retarding material arranged within the stiles and rails and panels, 20 a lock carrier formed inside a stile, pins extending through the door, and means on the ends of the pins for supporting the sides of the stiles and rails, and the interiorly arranged parts compactly together.
3. In a fire-door having hollow stiles and rails, interiorly re-inforced hinge bearings, a lock carrier or support carrying a lock independently of the stile, pins extending through the rails and stiles and having means 25 connected thereto for supporting the sides of the door.
4. In a fire-door, the combination of hollow steel stiles and rails, sheets of steel, wire-glass, and asbestos arranged interveningly 30 between the walls of the stiles and rails and panels, pins extending through the structure, and means on the end of the pins adapted to support the sides of the stiles and rails and the interior parts compactly together.
5. In a metallic door, hollow stiles and rails having interiorly re-inforced hinge bearings, a lock carrier or support carrying a lock independently of the stile, pins extending 35 through the rails and stiles, and means connected to the pins for supporting the sides of the door, and means for securing a molding to said pins.

6. In a metallic door, pins adapted to be inserted through the rails and stiles of the door and means engaging the ends of the pins 50 to support the outer sides of the door, and means communicating with the pins for supporting a molding or finish at each end thereof.

7. In a fire door, suitable hollow stiles and rails having interiorly reinforced hinge bearings, a lock carrier or support carrying a lock independently of the stile, sheets of fire retarding material arranged between the walls of the stiles and rails, and the panels of the door, and pins adapted to hold the parts 60 compactly together.

8. In a fire door, suitable hollow stiles and rails having interiorly reinforced hinge bearings, a lock carrier or support carrying a lock independently of the stile, sheets of fire retarding material arranged between the walls of the stiles and rails and the panels of the door, means for holding the parts compactly 65 together and for securing a molding or finish thereto.

9. In a fire door, suitable hollow stiles and rails having interiorly reinforced hinge bearings, a lock carrier or support carrying a lock independently of the stile, sheets of fire retarding material arranged between the walls 70 of the stiles, rails and panels of said door, pins inserted through the structure and having means on the end thereof for holding the parts compactly together.

10. In a fire door, suitable hollow stiles 80 and rails having interiorly reinforced hinge bearings, a lock carrier or support, sheets of fire retarding material arranged between the walls of the stiles, rails, and panels of said door, slotted pins inserted through the structure, wedges adapted to engage the ends of the pins, and means for holding the wedges 85 in position in the slots.

In testimony whereof, I the said J. OSCAR EMRICH have hereunto set my hand:

J. OSCAR EMRICH.
